US0D1012836S

(12) **United States Design Patent** (10) Patent No.: **US D1,012,836 S**
(45) Date of Patent: ** Jan. 30, 2024

(54) **RECHARGEABLE BATTERY**

(71) Applicant: **SONY GROUP CORPORATION**,
Tokyo (JP)

(72) Inventors: **Yosuke Matsuzaki**, Kanagawa (JP);
Hiroki Sato, Kanagawa (JP)

(73) Assignee: **SONY GROUP CORPORATION**,
Tokyo (JP)

(**) Term: **15 Years**

(21) Appl. No.: **29/796,921**

(22) Filed: **Jun. 28, 2021**

(30) **Foreign Application Priority Data**

(57) **CLAIM**

The ornamental design for a rechargeable battery, as shown and described.

DESCRIPTION

FIG. 1 is a front, top, left perspective view of a rechargeable battery showing our new design;

FIG. 2 is a rear, bottom, right perspective view thereof;

FIG. 3 is a front elevational view thereof;

FIG. 4 is a rear elevational view thereof;

FIG. 5 is a left side elevational view thereof;

FIG. 6 is a right side elevational view thereof; and,

FIG. 7 is a top plan view thereof.

The broken lines illustrating portions of the rechargeable battery form no part of the claimed design. Dot-dash broken lines defining the boundaries of the claimed design form no part of the claimed design.

1 Claim, 7 Drawing Sheets
